UNITED STATES PATENT OFFICE.

ELMER EDWARD ADIX, OF BOONE, IOWA.

HARROW.

1,034,558.

Specification of Letters Patent.

Patented Aug. 6, 1912.

Application filed May 23, 1910. Serial No. 562,829.

To all whom it may concern:

Be it known that I, ELMER EDWARD ADIX, a citizen of the United States, residing at Boone, in the county of Boone and State of Iowa, have invented a certain new and useful Harrow, of which the following is a specification.

The object of my invention is to provide a harrow of simple, durable and inexpensive construction, capable of being folded together, designed to be flexible when in an operative position and rigid when in a folded position.

A further object of my invention is to provide a harrow of similar sections designed to be connected and folded when not in operation and to be disconnected and in similar positions when in operation.

A further object of my invention is to provide a harrow with similar sections designed to be interchanged to form a four or three section folding harrow, also to provide a suitable folding evener bar with detachable sections to accommodate the different combinations of harrow sections.

A further object of my invention is to provide a flexible folding harrow whose sections are provided with teeth operating levers, the intermediate sections being provided with runners to carry the harrow when in a folded position.

A further object is to provide a flexible harrow in which the sections become rigid when the teeth are adjusted to positions from engagements with the ground surface, the intermediate sections when in said adjustment being raised to positions on the runners.

My invention consists in the construction, arrangement, and combination of the various parts of the device whereby the objects contemplated are attained, as hereinbelow more fully set forth, pointed out in my claims, and illustrated in the accompanying drawings, in which—

Figure 1 shows a plan view of my improved harrow partly broken away. Fig. 2 shows an end elevation of the same with the end sections in a folded position. Fig. 3 shows a plan view of my invention with three sections in operation. Fig. 4 shows a side elevation of one form of teeth supporting bar bearings. Fig. 5 shows an opposite elevation of same. Fig. 6 shows a side elevation of one form of teeth supporting bar bearings. Fig. 7 shows the opposite elevation of same. Fig. 8 shows a side elevation of one form of teeth supporting bar bearings. Fig. 9 shows an end elevation of one of the hooked connecting members. Fig. 10 shows a side elevation of same. Fig. 11 shows an end elevation of one of the bearing connecting members. Fig. 12 shows a side elevation of the same. Fig. 13 shows the section connecting members connected. Fig. 14 shows a detailed side elevation of one of the teeth operating levers. Fig. 15 shows an end elevation of same. Fig. 16 shows a detailed sectional view taken on the line 16, 16, of Fig. 3, looking in the direction of the arrows; and Fig. 17 shows a detail view of the bearing bars with ring attached.

vation of same. Fig. 8 shows a side elevation of one form of teeth supporting bar bearings. Fig. 9 shows an end elevation of one of the hooked connecting members. Fig. 10 shows a side elevation of same. Fig. 11 shows an end elevation of one of the bearing connecting members. Fig. 12 shows a side elevation of the same. Fig. 13 shows the section connecting members connected. Fig. 14 shows a detailed side elevation of one of the teeth operating levers. Fig. 15 shows an end elevation of same. Fig. 16 shows a detailed sectional view taken on the line 16, 16, of Fig. 3, looking in the direction of the arrows; and Fig. 17 shows a detail view of the bearing bars with ring attached.

Referring to the accompanying drawings I have used the reference numerals 10, 11, 12 and 13 to indicate the different harrow sections used in my improved harrow. The sections 14, 15, 16 and 17 comprising the evener bar, are detachably connected by the hinges 18 and the detachable pins 19. A cross bar 20 is connected to the evener sections 14, 15, 16 and 17 by the chains 21 and 21^a. The motive power is applied to the evener bar through the ring 22 and the links 23, which are connected to the cross bar 20, as shown in Fig. 1.

Each harrow section comprises five horizontal teeth supporting bars or members 23^a supporting teeth 23^b. The front members 23^a are mounted in bearings 24, the rear members in bearings 26 and the intermediate members in bearings 25—as best shown in Fig. 3. Retaining pins 27 and 28 pass through the members 23^a on opposite sides of the bearings 24, 25, and 26. The operating levers 29 are fixed to the rear teeth supporting members of each section, and are provided with hand operated pawls 30, which engage the pivotally mounted sectors 31 on the teeth supporting members. Secured to the sectors 31 in upright position are the bars 32, extending forwardly and upwardly and being rigidly connected by the bars 32 to the upwardly extended bars 34 which are pivotally mounted on the forward teeth supporting members, said construction firmly spacing the forward and rear teeth supporting members apart. Upwardly extending levers 35 are fixed to all but the rear teeth supporting members and are connected by the rods 36 which are pivotally connected to each of said levers, one

rod in each section being pivotally connected to the operating lever 29. Bars or rods 37 are pivotally connected to the bearings 24, 25 and 26 holding them apart in their proper relative positions and at the same time allowing them to move vertically, except when in one position of their adjustment, said position being hereinafter more fully described.

The upright levers 35 on the central teeth supporting bars in the sections 12 and 13 are provided with upwardly extended projections 35^a, said projections being designed to engage the bars 33 in the sections 10 and 11, when sections 12 and 13 are in folded position (see Fig. 2) to obviate the strain on the hinge connections between the outer and inner sections, as hereinafter more fully described.

The connections for securing the harrow sections together when not in operation comprise two members. In the bearing connection members which are applied to the intermediate sections 10 and 11 the numeral 38 indicates the bearing portions which fit over the ends of the forward and rear teeth supporting members 23^a. Runners 39 extend downwardly and rearwardly from said portions and are designed to receive the weight of the intermediate harrow sections 10 and 11 when the teeth 23^b are moved to positions from engagement with the ground surface. The extensions 40 on the bearing portions 38 are provided with cross bearings 41 and shoulders 42 for purposes hereinafter described. Inwardly extended bearing bars 38^a are fixed to the bearing portions 38 and are designed to seat in the teeth supporting bars 23^a to form wearing surfaces for some of the bearings. Said members are designed to be fixed to the forward and rear supporting members 23^a of the intermediate harrow sections 10 and 11 by pins 38^b extending through the openings 43 and 43^a in the portions 38, and bars 38^a. The hook connection members are applied to the inner ends of the front and rear supporting members 23^a in the end harrow sections 12 and 13, the bearing portions of which are indicated by the reference numerals 44. The extensions 45 on the connecting members 44 are provided with hooks 46 spaced apart from each other and are also provided with lugs 47 extending upwardly therefrom. Outwardly extending bars 44^a are fixed to the portions 44, said members being fixed to the supporting bars 23^a by pins 44^b extending through the openings 49 and also the openings 49^a in the bars 44^a. The bars 44^a, like the bars 38^a, above referred to, are adapted to seat in the members 23^a to form wearing surfaces for the bearings 24, 25 and 26—as shown in Figs. 4 and 5. The connecting members are connected as shown in the Fig. 13 of the drawings, the hooks 46 engaging the bearing members 41 to prevent upward movement of

the hooked connection members, the shoulders 42 engaging the hooks 46 and the lugs 47 engaging the outward extending portions 40 to prevent further inward movement of said hooked members to thus carry the end 70 harrow sections in a folded position as shown in Fig. 2 of the drawings.

The bearings 25 are provided with flanges 49^b extending outwardly from each side, each being provided with downwardly extending flanges 50 and 51. Pins 52 are mounted in said flanges 50 and 51 to form bearings for the rods or bars 37. Lugs 53 extending outwardly from the faces of the bearings 25 are designed to engage the pins 28, said pins being in engagement with said lugs when the supporting members 23^a are turned to positions with the teeth 23^b out of engagement with the ground surface.

With this arrangement of parts as above 35 described the supporting members 23^a being mounted in the bearings 25 and said members being connected by the rods 37, extending between the flanges 51 and 52, will be prevented from longitudinal movement by 90 said flanges, and will be free to move vertically except when the pins 28 engage the lugs 53, at which time the bearings 25 are stationary, the flanges 49^b then preventing vertical movement of the same, thus forming a substantially rigid harrow section. The bearings 24 and 26 are similar to the bearings 25, except that only one set of flanges 49, 50 and 51 extends outwardly therefrom. The flanges 54 extending outwardly from the bearings 24 are provided with openings 55 to which the chains 21 are attached.

To obtain suitable bearing surfaces for the bearings 24, 25 and 26, I have provided 105 together with the bearing bars 44^a and 38^a, the bars 25^b extending inwardly from the rings 25^a said rings being designed to fit on the ends of the teeth supporting bars 110 where said bars 25^b may form bearing surfaces for the bearings 24, 25 or 26. In positions where bars 38^a, 44^a, and 25^b cannot be used, I have provided bars 29^a designed to be seated in the teeth supporting bars and to be fixed thereto for bearing surfaces for 115 the bearings and for the rotatably mounted sector 31, as shown in Figs. 14 and 15.

To obtain a three section harrow, the section 10 is used in connection with the sections 12 and 13 in the manner above described. The evener bar sections 15, 16 and 17 are connected to the said sections by the chains 21 as shown in Fig. 3. Power is then applied to said evener sections through the ring 58 which is connected to said sections 125 by the chains 56 and the links 57.

In practical operation of my device, assuming that the four harrow sections are in extended position and disconnected from each other, the operating levers 29 are ad- 130

justed relative to the sectors 31 elevating the teeth to substantially vertical positions. The harrow is then drawn over the ground surface each teeth supporting bar being free to move vertically thus accommodating itself to the unevenness of the ground surface. When it is desired to pass through a gate or other narrow opening the levers 29 are moved forwardly thus changing the harrow teeth to position away from the ground surface and allowing the weight of the intermediate harrow sections 10 and 11 to rest upon the runners 39 and also moving pins 28 to position in engagement with the lugs 53 on the bearings 24, 25 and 26 to form a rigid construction of each section. During the normal use the front and rear bars are held in rigid relation to one another by the connecting member which bridges the intermediate bars, while the intermediate bars are left somewhat free to float up and down in accordance with the inequalities of the ground. But when the hand/lever is rocked forward to take the teeth out of engagement with the ground and to drop the harrow sections on its four runners, the pins on the tooth bar engage the stops on the bearings and twist those bearings sufficiently to tighten up all slack in the connections, yielding a connection which is rigid from end to end and which is supported at its four corners by the four runners. The hooked connection members on the end harrow sections are then applied to the bearing connection members on the intermediate harrow sections, said end harrow sections being lifted upwardly and tilted inwardly over said intermediate harrow sections to a folded position. The evener bar for each end harrow section folds with its corresponding harrow section. When the outer sections are in folded position, the projections 35² of the upright levers 35 rest on the bays 33 of the inner sections, thereby relieving the hinged connections 38 and 44 of undue strain. To again obtain an operative device it is only necessary to lower the end harrow sections and disconnect them from the intermediate sections and move the operating levers 29 rearwardly to bring the harrow teeth again in engagement with the ground surface. When it is desired to use three sections the intermediate section 10 is used in connection with the end sections 12 and 13 as above described, the evener section 14 being discarded. Power is then applied through the chains 56 the rods 57 and the ring 58.

I claim as my invention:

1. In a harrow, the combination of a series of bars provided with teeth, bearings wherein said bars may turn, connections between said bearings for holding the same in predetermined relation, and a rigid connection between the front and rear bar of

said series for holding the same apart in fixed relation, a lever fixed to the rear bar, upright arms fixed to the remaining bars and links for connecting the said lever with said arms whereby the bars are simultaneously adjusted upon operation of said lever to alter the declination of the teeth. 70

2. In a harrow, the combination of a series of bars provided with teeth, bearings wherein said bars may turn, connections between said bearings for holding the same apart in predetermined relation, a rigid connection from the front to the rear bars of said series and bridging the intermediate bars, and means for rotatably adjusting 80 said bars simultaneously to alter the declination of the teeth. 75

3. In a harrow, the combination of a series of rotatable bars provided with teeth, bearings for said bars each having an extension arranged for receiving a link, links connecting said bearings and holding the same in predetermined relation, a lever fixed to the rear bar, upright arms fixed to the remaining bars, links connecting said lever with said arms whereby the bars are simultaneously tilted upon operation of said lever and means associated with each bar for limiting the rotary movement thereof. 85

4. In a harrow, the combination of a series of bars provided with teeth, bearings wherein said bars may turn, said bearings having side flanges, links pivoted to said bearings under said flanges to hold said bars in predetermined relation, a lever fixed to the rear bar, upright arms fixed to the remaining bars, means connecting said lever with said arms whereby the bars are simultaneously tilted on operation of said lever, a rigid connection between the front and rear bars for holding the same apart and runners on the bearings of the front and rear bars arranged to support the harrow when the teeth are at the limit of declination. 100 105

5. In a harrow, the combination of a bar provided with teeth, a member seated in the end of said bar and having a projection adapted for receiving a connecting link, and a bearing member wherein said bar may turn, said end member having a part arranged as a wearing surface for said bearing. 110 115

6. In a harrow, the combination of a harrow section comprising a series of bars provided with teeth, pivotal link connections between said bars, and a rigid connection between the front and rear bars for holding the same apart in fixed relation, said rigid connection having end bearing portions whereby it is rotatably mounted on said front and rear bars. 120 125

7. In a harrow, the combination of a series of bars provided with teeth, pivotal link connections between said bars, a rigid connection between the front and rear bars 130

for holding the same apart in fixed relation, said rigid connection having end bearing portions whereby it is rotatably mounted on said front and rear bars, stops on said bearings, pins on said bars, and means for rotating the toothed bars until said pins engage with said stops and tighten the pivotal link connections between said bars.

8. In a harrow, the combination of a series of toothed bars, bearings for the ends of each bar, pivotal link connections between said bearings, a rigid connection between the front and rear bars for holding the same apart in fixed relation, said rigid connection having end bearing portions whereby it is rotatably mounted on said front and rear bars, an upstanding arm fixed to each bar, a hand lever operatively connected to move said arms and to rotate their attached bars, lugs on said bearings, pins on said bars, said lugs and pins being

in position to tighten the connections between said bearings when the teeth of said tooth bars are swung out of engagement with the ground.

9. In a harrow, the combination of a harrow section comprising a series of bars provided with teeth, bearings for rotatably supporting said bars, connections between said bearings for holding the same apart in predetermined relation, means for rotatably adjusting said bars to alter the declination of the teeth, pins extending through said bars adjacent to said bearings, and stops on said bearings adapted to engage said pins for limiting the rotary movement of the bars.

Des Moines, Iowa, May 10, 1910.
